UNITED STATES PATENT OFFICE.

GEORGE J. KELLER, OF NEWARK, NEW JERSEY.

DESIGN FOR A WATCHCASE.

Application filed February 2, 1923. Serial No. 5,054. Term of patent 14 years.

To all whom it may concern:

Be it known that I, GEORGE J. KELLER, a citizen of the United States, residing in the city of Newark, in the county of Essex and State of New Jersey, have invented a new, original, and ornamental Design for a Watchcase, of which the following is a specification, reference being had to the accompanying drawings, forming a part thereof.

In the drawing,

Figure 2, represents a rear elevation; and Figures 3 and 4 represent side elevations, respectively.

I claim:

The ornamental design for a watchcase, as shown.

GEORGE J. KELLER.
